CLAIM

The ornamental design for a stackable bin, as shown and described.

DESCRIPTION

FIG. 1 is a perspective view of a stackable bin showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a cross-sectional view of the stackable bin along line 8-8 of FIG. 2.

The broken lines shown in the drawings are for the purpose of illustrating portions of the stackable bin that form no part of the claimed design.

1 Claim, 8 Drawing Sheets
